UNITED STATES PATENT OFFICE

HERMAN MILLER, OF ZEELAND, MICHIGAN

DESIGN FOR A COMBINED CLOCK CASE AND SHELVING

Application filed March 23, 1931. Serial No. 39,205. Term of patent 3½ years.

To all whom it may concern:

Be it known that I, HERMAN MILLER, a citizen of the United States, residing at the city of Zeeland, in the county of Ottawa and State of Michigan, have invented a new, original, and ornamental Design for a Combined Clock Case and Shelving, of which the following is a specification, reference being had to the accompanying drawing, forming a part thereof.

The figure is a front perspective view of a combined clock case and shelving showing my new design.

I claim:

The ornamental design for a combined clock case and shelving as shown.

HERMAN MILLER.
